BOBBIN STRIPPER

Edgar Allen Terrell, Charlotte, N. C., assignor to
 The Terrell Machine Company, Charlotte, N. C.,
 a corporation

Application May 29, 1934, Serial No. 728,151

4 Claims. (Cl. 28—20)

This invention has relation to that type of 5
 bobbin stripping machines having blades or the
 like by which the bunch of weft or filling is re-
 moved from the bobbin-barrel by a scraping ac-
 tion taking place lengthwise along the bobbin
 barrel, and the object of this invention is to pro-
 vide a head-rest for the bobbin which shall have
 certain advantages hereinafter described, over the
 usual type of head-rest, such for instance as is
 shown in my former Patent No. 1,740,127, dated
 December 17, 1929.

In the drawing annexed, Fig. 1 is a side elevation
 of a portion of a bobbin stripping machine
 showing my invention applied thereto, and Fig. 2
 is a plan view of the same.

Referring to the drawing annexed by reference
 characters, 5 designates the two reciprocating
 scraper blades having their inner ends provided
 with arcuate scraping edges, as usual. These
 20 blades are mounted in supports 6 which are sta-
 tionary parts of the machine frame. Mounted
 on the supports 6 is a pair of plates 7 which to-
 gether form a head-rest for the bobbin head, one
 25 of these blades being attached to each of the sup-
 ports 6 by a lag bolt 8 which passes through a
 longitudinal slot 9 in the plate, and is tapped into
 the support 6.

Each head supporting plate 7 is inclined up-
 wardly toward the center of the path of the
 30 bobbin, the head of the bobbin being shown in
 dotted lines at 10. The seats for the plate 7 are
 inclined their full length so as to provide a solid
 substantial support for the plates, and in order
 35 to prevent the plates turning on the bolts as piv-
 ots, I provide each support 6 with an integral
 flange 11 which engages the adjacent edge of its
 companion plate. The inner, upper edges of the
 40 plates 7 engage the usual rings on the head of the
 bobbin and thus support it in proper position
 for its barrel to be grasped by the scraping blades.
 45 Plates 7 are made alike at both ends so that
 they are not only interchangeable, but reversible,
 end for end, thereby facilitating assemblage of
 the parts.

By using two blades, one at either side of the
 path of the bobbin and making each one inde-
 50 pendently adjustable toward and from the cen-
 ter of the path of the bobbin, it will be seen that
 the bobbins may be nicely centered with refer-
 ence to the scraping blades irrespective of the
 size of the bobbin head. This independent ad-

justability of the head-rest plates does away with
 the necessity of exercising that great accuracy in
 designing the head-rest that is needed where the
 head-rests are made stationary. Also, the ad-
 justable plates are highly desirable in that they 5
 permit the mill to adjust the machine to suit the
 head sizes of its bobbins, thereby doing away with
 the expense and delay of having the head rests
 removed from the machine and reshaped.

By inclining the head-rest plates upwardly to- 10
 ward the center of the bobbin path I get a fur-
 ther important advantage in that I provide a
 wider throat space between the two supporting
 plates than is possible to obtain with the former
 horizontal head-rests, and thus provide a wider 15
 space for misplaced yarn-bunches to fall through.
 It occasionally happens that yarn-bunches will
 be flipped over onto the head-rest and lodged
 thereon with the result that the next bobbin de-
 livered onto the head-rest will have its head 20
 propped up sufficiently to prevent the bobbin
 barrel being embraced properly by the scraper
 blades. It will be seen therefore that it is highly
 desirable to have the space between the head-
 rest elements as wide as possible as the wider it 25
 is the less danger there is that a misplaced yarn
 bunch will lodge on the head-rest members.

I claim:

1. In a bobbin-stripper, frame members, a pair
 of stripping blades, and a bobbin head-rest adja- 30
 cent said blades, said bobbin head-rest consisting
 of a pair of plates both inclined upwardly and
 supported on the frame members, one at each
 side of the bobbin path, and means whereby said
 plates are rendered adjustable toward and from 35
 the bobbin path.

2. The structure recited in claim 1, said plates
 being inclined upwardly toward the center of the
 bobbin path.

3. The structure recited in claim 1, the means 40
 for adjustably fastening the plates to the frame
 members consisting of longitudinal slots in the
 plates and bolts passing therethrough and serv-
 ing to clamp them against the frame members,
 said frame members being provided with depend- 45
 ing flanges which abut the side edges of the
 plates.

4. The structure recited in claim 1, said blades
 being each also removable and reversible end for 50
 end, both ends of each blade being shaped alike.

EDGAR ALLEN TERRELL.
